(57) **CLAIM**

The ornamental design for a shock protective vacuum-formed package for disc drives, as shown and described.

DESCRIPTION

FIG. 1 is a perspective view of a shock protective vacuum-formed package for disc drives showing our new design, in an open position;

FIG. 2 is a top plan view thereof;

FIG. 3 is a top plan view thereof; in a closed position;

FIG. 4 is a left side elevational view thereof;

FIG. 5 is a front elevational view thereof;

FIG. 6 is a bottom plan view thereof;

FIG. 7 is a right side elevational view thereof;

FIG. 8 is a rear elevational view thereof;

FIG. 9 is a perspective view of a second embodiment of FIG. 1, in an open position;

FIG. 10 is a top plan view of FIG. 9;

FIG. 11 is a top plan view of FIG. 9, in a closed position;

FIG. 12 is a left side elevational view of FIG. 11;

FIG. 13 is a front elevational view of FIG. 11;

FIG. 14 is a bottom plan view of FIG. 11;

FIG. 15 is a right side elevational view of FIG. 11; and,

FIG. 16 is a rear elevational view of FIG. 11.

The broken line showing of indicia and description is for illustrative purpose only and forms no part of the claimed design.
